UNITED STATES PATENT OFFICE.

WILLIAM L. SWARTZ, OF UTICA, NEW YORK, ASSIGNOR TO SAVAGE ARMS COMPANY,
OF UTICA, NEW YORK, A CORPORATION OF NEW YORK.

FIREARM.

1,141,285.

Specification of Letters Patent. Patented June 1, 1915.

Application filed March 24, 1914. Serial No. 826,883.

To all whom it may concern:

Be it known that I, WILLIAM L. SWARTZ, a citizen of the United States, residing at Utica, in the county of Oneida and State of New York, have invented certain new and useful Improvements in Firearms, of which the following is a specification.

This invention relates to safety locking devices for fire-arms, and particularly fire-arms of the automatic pistol type, wherein there is frequently employed as a part of the grip a lever or other movable member which, when moved in the act of gripping the gun in firing, disestablishes the safety lock, which is otherwise active to prevent unpre-meditated firing.

I aim to provide a simple and efficient safety locking means for a gun of the character of that set forth in the patent to Searle, No. 936,369, but the invention is to be understood as applicable to any gun wherein the manually actuated controlling portion of the improved means is adaptable to form with a part of the gun frame the grip of the gun.

In the accompanying drawing, Figure 1 is a side elevation of the improved gun, showing certain parts broken away and others in section, the safety means being in the position for allowing the gun to be fired. Fig. 2 is a fragmentary side elevation of the gun, showing said means in the locking position; Fig. 3 is a rear elevation of a part of said means; and, Fig. 4 is a plan view of said means and a part of the firing-mechanism-including train.

The gun frame *a*; barrel *b*; sliding breech structure *c* having the removable plug *d*; the firing-mechanism-including train of parts comprising, with the cocking lever *e* pivoted in plug *d* and having connected therewith the firing-pin (not shown), the sear *f*, the sear-trip *g* and trigger *h*, and the rod or bar *i* arranged to slide in a horizontal guideway shown in one side of the frame and connected with the sear-trip; and the pivoted detent *j* movable to the horizontal position, to lock the breech-structure and cocking lever and obstruct the sliding movement of bar *i* and so block the firing movement of the firing train, and to the vertical position to release these parts (in the case of the firing train, having a hole *k* to receive the rear end of said rod and thereby permit its sliding movement) are or may be

all substantially the same as in the patent to Lang No. 1082961.

In the present instance the rear end of the bar *i* is forked, one leg *i''* of such forked portion being adapted to abut the detent *j* or register with its hole *k*, according to the position of the detent, and the other leg *i'''* being arranged inwardly lateral of the leg *i''*.

As shown in Fig. 1 a space exists between the rear end of leg *i''* and the opposite face *j'* of the detent *j*. This space is adapted to receive a lug *l* on the upper end of a vertically sliding angular bar *m* whose upper half (approximately) *m'* is outwardly offset with respect to its lower half *m''*; the upper half *m'* of this bar moves in a guideway or slot *n* formed in the same side of the frame as and meeting the guideway for the bar *i*, the outer surface thereof being substantially flush with the corresponding surface of the frame so that the handle portion of the detent *j* may overlap it when occupying the position shown in the drawing, while its lower half *m''* bears against the inner surface of the frame. The normal position of the bar *m* is that shown in Fig. 2, where the lug *l* is interposed between the leg *i''* of bar *i* and the detent *j* and abuts the under side of a shoulder *a'* on frame *a*; bar *m* may move downwardly to a limit afforded by the contact of its shoulder *m'''* with the lower end of the slot *n* in which position lug *l* is withdrawn from between leg *i''* of bar *i* and the detent.

o is a safety lever for controlling the position of bar *m*. It is fulcrumed at its lower end on a pin *p* in the grip forming portion of the frame and at the back thereof, being shaped to correspond with the contour of the grip. Between the near side of this lever and the near wall of the grip portion of the frame the part *m''* of the bar *m* is confined. The lever *o* has a slot *q* inclined downwardly with respect to the path of travel of the bar *m*, which has a stud *r* received by and approximately fitting said slot.

s is a spring coiled about pin *p* and having one end bearing against the lever *o* and the other against a stud *t* and normally pressing the lever rearwardly on its fulcrum (Fig. 2). Owing to the disposition of the slot *q* relatively to the path of travel of the bar *m* it will be seen that in the normal

position of the lever said bar is held in its elevated position, blocking the rearward movement of bar *i* and hence of the entire firing-mechanism-including train; and that the retraction of the bar *m* downwardly out of blocking relation to bar *i* is accomplished by pressing the lever *o* forward, as an incident to properly gripping the gun for pulling the trigger in the act of firing.

10 The sides of the slot *q* act, cam-fashion, on stud *r* in the back and forth movements of the lever.

The rearward movement of the lever *o* under the influence of the spring *s* is limited by the bar *m* which at this time abuts the fixed shoulder *a'*, while the stud *r* and the lower side of slot *q* abut each other.

In the present instance, inasmuch as the extension *e'* of the cocking lever cannot obtain its cocking action by contact with the frame (as in the Searle and Lang patents above mentioned), said frame being cut away to accommodate the lever *o*, the lever itself has a rounded bearing surface *o'* to receive the wiping contact of said extension.

Having thus fully described my invention, what I claim as new and desire to secure by Letters Patent is:-

1. In combination, with a gun having a

frame and a movable firing-mechanism-including train, means for blocking the firing movement of said train including an upright bar up-and-down movable into and out of movement-blocking relation to said train and having its upper portion laterally offset, the frame having a guideway receiving said offset part of the bar, and manually actuated actuating means for said bar, said means and the frame side below the guideway confining the lower part of said bar between them.

2. In combination, with a gun having a frame and having in one side of said frame guideways meeting at an angle to each other, a movable firing-mechanism-including train including a bar slidably arranged in one of said guideways, and means for blocking the firing movement of said train including another bar slidably movable in the other guideway into and out of movement-blocking relation to the first bar.

In testimony whereof I affix my signature in presence of two witnesses.

WILLIAM L. SWARTZ.
